KNITTING NEEDLE

Julius R. Bux, Melrose, Pa., assignor to J. R. Bux & Son, Philadelphia, Pa., a copartnership
Filed Feb. 4, 1965, Ser. No. 430,397
3 Claims. (Cl. 66—119)

ABSTRACT OF THE DISCLOSURE

A spring beard knitting needle of a single piece of wire in which the beard is connected to the shank by a resilient coil.

This invention relates to knitting needles for use in knitting machines and more particularly to bearded knitting needles.

Bearded knitting needles are in common use on circular and flat bed knitting machines. Serious difficulties have been encountered because by reason of repeated stressing of the needles, and particularly the spring bearded needles, at the arched turn, these needles crystallize and break. This breaking results in loss of machine time during replacement, the labor cost for replacement as well as added cost for the needles themselves.

It is the principal object of the present invention to provide improvements in knitting needles of the bearded type which will greatly increase the useful life of the needle.

It is a further object of the present invention to provide improvements in knitting needles of the bearded type in which enhanced resiliency is provided in the needle without interfering with the operation of the needle.

Other objects and advantageous features of the invention will be apparent from the description and claims.

The nature and characteristic features of the invention will be more readily understood from the following description taken in connection with the accompanying drawings forming part thereof, in which;

FIGURE 1 is a perspective view greatly enlarged, of a knitting needle in accordance with the invention;

FIG. 2 is a side elevational view, enlarged, of the operating end of the knitting needle shown in FIG. 1;

FIG. 3 is a horizontal sectional view, further enlarged, taken approximately on the line 3—3 of FIG. 2; and

FIG. 4 is a top plan view, enlarged, of the portion of the knitting needle shown in FIG. 2.

It should, of course, be understood that the description and drawings herein are illustrative merely, and that various modifications and changes can be made in the

2

structure disclosed without departing from the spirit of the invention.

Referring now more particularly to the drawings, a preferred embodiment of the invention as applied to a spring bearded needle 10 is shown. The knitting needle 10 is preferably made of spring steel wire and has a shank 11, preferably round in cross section. The shank 11 at one end has an angularly disposed portion 12 for anchoring the needle 10 in the knitting machine (not shown).

The needle 10 has a beard 15 with an inturned point 16 for reception in a groove 17 in the shank 11. The beard 15 at the portion remote from the point 16 is joined to an extension 18 of the shank 11 of reduced cross section by a single spiral resilient turn 19. The diameter of the turn 19 is such as to space the end of the beard 15 from which turn 19 extends at the desired distance from shank 11 to provide an eye for the accommodation and retention of the yarn when the point 16 is engaged in the groove 17. Thus the coil or turn 19 is of substantially the same width as the needle eye. The turn 19 provides a resilient hinged connection which effects a distribution of the stress during flexing and avoids the concentration of the flexing at the tip as in prior needles.

I claim:

1. A knitting needle of the spring bearded type made from a single piece of spring wire having a shank with a groove, a beard having an end for engagement in the groove, and a resilient coil connecting said shank and said beard remote from said end and providing distribution of the stresses upon movement of said beard.

2. A knitting needle as defined in claim 1 in which said coil is a single turn.

3. A knitting needle as defined in claim 1 in which said coil is a single turn of substantially the same width as the needle eye.
